UNITED STATES PATENT OFFICE.

FRANK O. SKOOG, OF CHICAGO, ILLINOIS.

MACHINE FOR TUCK-POINTING.

1,055,565.

Specification of Letters Patent.

Patented Mar. 11, 1913.

Application filed November 1, 1911. Serial No. 657,945.

To all whom it may concern:

Be it known that I, FRANK O. Skoog, a subject of the King of Sweden, residing at Chicago, in the county of Cook and State 5 of Illinois, have invented certain new and useful Improvements in Machines for Tuck-Pointing, of which the following is a specification.

My invention relates to masonry work and 10 has particular reference to a machine for "tuck pointing," or one which feeds the mortar or plastic material to the operator's trowel, pointer or other tool used for applying mortar, cement and the like.

15 The particular object of the invention is to provide a machine for repairing or "pointing up" the crevices formed between bricks or blocks where the mortar or binder has fallen or crumbled away through the 20 action of the weather. Where the walls of a large office building are to be repaired in this manner the work consumes considerable time and energy where the workman must mix his mortar in small quantities at frequent intervals, carry it on a mortar board, 25 and pick it up a little at a time by his pointing tool. The present invention is designed to flow the mortar onto the tool and enable the operator to wield the tool uninterrupted 30 in applying the binding material neatly, rapidly and with a saving of material spilled through the old methods of application.

With the above-named objects in view my 35 invention consists in the novel construction, combination and arrangement of parts hereinafter described in detail, illustrated in the accompanying drawings and incorporated in the appended claims.

40 In the drawings—Figure 1 is an elevation, partly in section, of a machine embodying my invention. Fig. 2 is a section taken substantially on line 2—2 of Fig. 1. Fig. 3, is an exterior view of the nozzle with a section 45 of the hose attached thereto. Fig. 4 is an enlarged longitudinal section through a broken away portion of the nozzle. Fig. 5 is a perspective view of a pointing tool together with the clamp by means of which 50 it is attached to the nozzle. Figs. 6 and 7 are two forms of cross-section of the pointing tool. Fig. 8 is a plan view of the closer for the mortar receptacle of the machine.

55 The machine embodying the present invention comprises a receptacle or mortar tank adapted to contain a substantial quan-

60 tity of binder such as mortar or cement, a mechanism for forcing this material through a hose or flexible tube to the operator's pointing-tool and various novel features for facilitating this work.

In the several views 2 represents a "horse" or supporting legs for the machine, which is provided with a flange or brackets 3 which rest on the horse. The parts 3 are riveted to a mortar-receptacle or tank 4 which is preferably made of cylindrical form with a concave bottom portion 5 riveted to the body of the tank by rivets 6. The heads of these rivets within the tank are utilized as supports or ledges for a screen 7 through which the plastic material must pass to an opening 8 in the bottom of the tank. This opening is provided with a nipple or short section of pipe 9 which is riveted to a flange 10 formed by bending downward the edges of the opening 8. To the nipple is attached a hose or flexible tube 11, one end of which is shown in Fig. 1 while its opposite end is shown in Fig. 3, 70 75 the intermediate portion being broken away. The machine is preferably placed on the roof of a building to be pointed up so as to obtain the assistance of the force of gravity in flowing the material through the hose 85 11 to its nozzle shown in Figs. 3 and 4 which will follow the operator along the wall or structure upon which the work is to be done. The nozzle has at least a portion thereof of rectangular form in cross-section, as indicated by the configuration of 90 the structure shown in Fig. 5.

Within the tank is fitted a cover for the plastic material, a follower or a presser-foot for an operating screw. This cover, follower or presser-foot is composed of a wooden slab 13, the upper surface of which has a covering 14 of sheet metal. A similar covering 15 is provided for the under-side of the follower. The diameter of the portion 13 is a little less than the portions 14 and 15, which provides a channel in the edge of the follower between its plates 14 and 15. In this channel is placed a packing-ring 16. In the follower is an opening 17 provided with a cover or closer 18 that is clamped onto the top of the follower by means of a screw 19 provided with a lever or hand-wheel 20. This screw has threaded engagement with a bar 21 the ends of which are held by a pair of brackets 22 secured to the follower. Pressure is brought to bear upon

the follower and the mass of mortar or other plastic material, for the purpose of forcing same through the hose 11, by the lower end 23 of a screw 24. This screw has threaded engagement with a sleeve or bushing 25 splined at 26 to a hub 27 of a gear-wheel 28. The sleeve is thus rotatable with the gear wheel 28 and is movable longitudinally in the hub 27. On the upper end of the sleeve 25 is a flange 29 which contacts with the upper end of the hub 27. On this flange is mounted a bearing-ring 30. Above the latter is another and similar ring 31, and between the two rings are interposed anti-friction balls 32, the lower ring to rotate with the sleeve and the hub while the upper remains stationary. Against the upper ring the lower end of a spring 33, coiled around the screw 24, is brought to bear. The upper end of the spring bears against a cross-beam 34 through which an opening 35 is made for the screw 24. The beam 34 is secured to upright bars 36 and 37. The lower end of the hub 27 of the wheel 28 is supported on a bar 38 riveted at 39, 39 to the upright frame-bars 36 and 37, the hub being engaged by a flange 40 on a disk 40, an annular groove 41 being formed in the hub to receive the lugs. The disk 40 is secured by means of rivets 42. The screw 24 is held against rotation by an arm 43 secured to the screw and provided with a fork 44. The latter has slidable engagement with a post 45 bolted at 46, to the upright 36. The gear wheel 28 is rotated by means of a pinion 47 keyed to a shaft 48 mounted in bearings 49. The shaft has a squared end 50 to which a crank 51 is applied. On the shaft 48 is also keyed a small gear-wheel 52 which meshes with a large gear-wheel 53 keyed to a shaft 54 mounted in bearings 55 secured to the upright 37. The shaft has also a bearing in a drop bracket or arm 56 secured to the cross-bar 38. The shaft 54 is held against longitudinal movement in one direction by a head 57 which bears against the arm 56, and against such movement in the opposite direction by a washer 58 shrunk on the shaft. The large wheel 53 and its shaft 54 rotate idly when the crank 51 is attached to the shaft 48, but when the crank is applied to the squared end 50 of the shaft 54 and rotated the large wheel becomes the driving wheel rotating the smaller wheel and its shaft at a considerably higher speed than when the crank is applied to the upper shaft. The crank is operated on the latter when the screw is forced downwardly against the follower on the plastic mass, or when the greater power is required, and the large wheel is used as the driving wheel for the purpose of rapidly returning the follower to the top of the tank preparatory to refilling same.

Referring, now, to the nozzle 12 to which one end of the hose or flexible tube 11 is attached. Through one of the sides, the upper one labeled 60 in Figs. 3 and 4, is an opening or slot 61 and in the inner faces of parallel sides 62 and 63 of the nozzle, are grooves 64, one of which is shown in Fig. 4. In said slot and grooves is mounted a gate-valve 65, which is operated to open or close the passage through the nozzle, or to start and stop the flow of plastic material therethrough. The gate-valve 65 is held normally raised or open by a spring 66 mounted on a clamp 67 attached to the nozzle. An arm 68 is secured to a clamp 69 on the nozzle, and on the free end of this arm is a lug or stop 70 which limits the opening movement of the valve 65 or prevents the valve from moving far enough outwardly to become disengaged from its slot. Between the bracket 69 and a similar bracket 71 is held a packing-disk 72 which prevents leakage of material through the gate-valve opening in the nozzle.

At the outlet or tip end of the nozzle 12 is secured the "pointing" tool or trowel. This tool, 73, is held on the nozzle by means of a double clamp 74 having ears 75 and 76 with bolt-holes 77 therein for bolts 78. The form of the tool 73 may be varied in numerous ways as to its form, but for pointing purposes the construction shown is the accepted form either flat or curved transversely as indicated in Figs. 6 and 7 where 73 indicates the flat form and 73' the concave. The flat form is about $\frac{3}{2}$ " in thickness and about $1\frac{1}{2}$ " in width while the curved form is usually only $\frac{1}{2}$ " in width. The concave form is used with the concave side toward the spaces between bricks to be filled in and to form a slightly projecting bead outside of the plane of the wall surface. In Fig. 1 a fastening collar 79 is used for holding the hose on the tank nipple, and a similar collar 80 secures the hose to the nozzle.

81 and 82 are struts to which the lower end 23 of the screw 24 is swiveled, and 83 represents a shallow recess for the end of the screw in the follower.

In operation the machine will be placed, preferably, at some point above where the operator handles the nozzle, the follower will be raised to the upper end of the receptacle 4 and the cover 18 will be removed when the receptacle 4 may be filled with the plastic material. After the receptacle is filled an operator will manipulate the crank 51 to force the material through the hose into the nozzle. The operator of the latter will control the flow by manipulation of the spring 66 to open or close the valve 65, which may be done simultaneously with the guiding of the tool 73 by grasping the nozzle at the spring 66, or including both nozzle or 130

spring in the grip. Any excess force of pressure will be taken up by the spring 33 which will be tensioned to yield only to such excess pressure, or, in other words, permit the 5 sleeve 25 to rise if the screw is advanced too rapidly. Such rise of the sleeve will also be notice to the operator of the crank to ease up on his work. If the machine is operated by a motor controlled by the operator of the 10 nozzle the rise of the sleeve may by suitable well known means cause a break in the current or a shutting off of power from the motor, in which event no attendant is necessary for the purpose of operating the crank. 15 When the receptacle 4 has been emptied of its contents the follower may be quickly raised by applying the crank to the squared end 59 or driving the wheel 52 by the wheel 53 in the proper direction to return the 20 screw to its raised position. The confinement of the mortar, or whatever plastic binder is used, in the closed vessel 4 will prevent the mass from drying or hardening as rapidly as when spread upon a mortar 25 board and larger quantities may be prepared at each mixing of binder materials.

Having thus described my invention, I claim as new and desire to secure by Letters Patent—

30 1. The combination with a pointing tool or trowel, of a container for binder material, a nozzle upon which said tool or trowel is mounted, a flexible tube for conveying said material to said nozzle, means in said

nozzle for controlling the flow therethrough, 35 and means for forcing said material from said container through said nozzle.

2. The combination with a mason's trowel or pointing tool, of a receptacle for plastic material to be applied with the aid of said 40 tool, a nozzle upon which said tool is mounted, a conduit between said receptacle and tool, means for forcing said material through said conduit, and a valve on said nozzle for controlling the flow through said 45 conduit, or for checking and releasing the flow of material under the operation of said forcing means.

3. The combination with a trowel or pointing tool, of a receptacle for binder 50 material, a conduit between said receptacle and tool, a follower in said receptacle for creating pressure on a mass of plastic material to force it through said conduit, a crank-operated screw for moving said 55 follower, a yieldingly mounted nut or threaded sleeve for said screw to take up excess follower pressure under the action of the screw-operating mechanism, and a valve-controlled outlet for said pointing tool through which 60 the material is flowed onto said tool.

In testimony whereof I have hereunto set my hand in the presence of two subscribing witnesses.

FRANK O. SKOOG.
